UNITED STATES PATENT OFFICE.

CHARLES DAVID BONSALL, OF CHICAGO, ILLINOIS, ASSIGNOR TO UNION METAL PRODUCTS COMPANY, OF CHICAGO, ILLINOIS, A CORPORATION OF DELAWARE.

PANEL BRACING IN HOPPER DOORS FOR RAILWAY CARS.

Application filed August 17, 1925. Serial No. 50,872.

The invention relates to a railway dump car having a "door" forming a part of the car for retaining the load therein, which door is provided with hinges adjacent one of its sides and is capable of being "dropped" or swung open so that the load in discharging slides or passes over the upper surface of the door. Any means of raising the door to the closed position, and any means for locking and releasing the door, may be employed with my device. A door for this purpose must be very strong and durable because:

First: It is part of the floor of the car and as such must sustain the load as well as the impact blow when the car is in motion.

Second: The car is frequently loaded from chutes or tipples from a height of ten feet or more, causing the load to be dropped directly upon the doors.

Third: Clam shell buckets are frequently used to unload such cars and it is not uncommon for these buckets to rest upon and drag over the doors.

Fourth: When the door suddenly comes to rest after being dropped it is not only subjected to a severe shock, but it must sustain the severe impact thrust of the load which, of course, follows the door.

Fifth: As the load is theoretically equally distributed, the door must be strong over its entire area and must be capable of transmitting the resulting strains to the car body without much deflection and no substantial distortion. Any bending of the door or drooping of the corners would cause a leak of the lading, especially of such fine material as sand, chats, etc. Any bending or warping might interfere with the complete closing and locking of the door.

As it costs as much to haul a ton of car as it does to haul a ton of paying freight, it is imperative that the car and any part thereof be as light as possible. Furthermore, the total weight of car and freight is determined by the strength of certain standard axles so that the lighter the car the greater amount of freight a given car will be allowed to carry. With my arrangement I obtain a strong, light and inexpensive door.

In the drawings:

Fig. 1 shows a door formed according to my invention.

Fig. 2 is a section on line 2—2 of Fig. 1.

Fig. 3 is a section on line 2—2 of Fig. 1 showing a modification.

Fig. 4 is a section on line 2—2 of Fig. 1 showing a flat plate reinforcement.

Fig. 5 is a section on line 2—2 of Fig. 1 showing a flat plate reinforcement to a modification.

In order to conserve space it may be advisable to reverse the direction of some of the panels without diminishing the strength of the panel as an entirety. Suggestions along this line are shown in Fig. 3. Panels of different depths are thus obtained.

Any number of panels may be used of various depths, position and shape and still come within the scope of this invention.

Numeral 7 is the side walls of a panel pressed from the main portion 6 of the plate. Numeral 8 is the side walls of a panel pressed from the elevated portion of the first mentioned panel and numeral 9 is the side walls of a panel pressed from the elevated portion of the last mentioned panel. Margins 10 and 11 are thus formed between panel within panel.

The margins 13 and 14 at the sides of the door are wider than the margins 6, 10 and 11 at the ends of the door. The walls 7, 8 and 9, parallel to the ends of the door, are then closer together than the walls 16, 17 and 18, parallel to the sides of the door.

A sheet 20 is positioned below the embossed plate and is secured to any one of the flat margins and a strut 21 may be placed between the plate and the sheet so that the plate and sheet are the compression and tension members, respectively, of a truss. I have used the terms "plate" and "sheet" for convenience in describing the two members but there is no difference in the terms as far as this invention is concerned.

The lower sheet (22) may be embossed similarly to the upper plate so as form a deeper truss. It is not essential that the embossments of the plate and sheet be exactly alike, nor need they necessarily have the same number or depth of embossments.

In some cars the hoppers are narrower at the bottom than at the top of the door opening and the door is made substantially the same shape as the hopper opening. It is preferable to have the embossed panels conform to the shape of the door, or at least, approximately so as illustrated.

Fig. 3 shows a modified form wherein the deeper panels are positioned adjacent the sides of the door and the shallower panels are placed within the deeper panels and the sheets (or plates) are secured together adjacent the center of the door.

Fig. 4 shows a construction wherein one of the plates of Fig. 2 is used in combination with a flat sheet (or plate) 20. A strut, such as 21, may be used.

Fig. 5 shows a construction wherein one of the plates of Fig. 3 is used in combination with a flat plate (or sheet) 20. The component members may be secured together adjacent the center, as shown.

I claim:

1. A plate metal door for a railway car having an embossed panel pressed from the plane of the plate with flat margins surrounding said panel, an embossed panel pressed from the first mentioned panel with flat margins surrounding the last mentioned panel, a similarly embossed metallic sheet secured to said plate with the embossments projecting in the opposite direction to those of the plate, and a strut between said plate and said sheet.

2. A plate metal door for a railway car having an embossed panel pressed from the plane of the plate with flat margins surrounding said panel, an embossed panel pressed from the first mentioned panel with flat margins surrounding the last mentioned panel, said embossed panels projecting in the same direction, a similarly embossed metallic sheet secured to said plate with the embossments projecting in the opposite direction to those of the plate, and a strut between said plate and said sheet.

40 3. A plate metal door for a railway car having an embossed panel pressed from the plane of the plate with flat margins surrounding said panel, an embossed panel pressed from the first mentioned panel with flat margins surrounding the last mentioned panel, said embossed panels varying in depth, a similarly embossed metallic sheet secured to said plate with the embossments projecting in the opposite direction to those of the plate, and a strut between said plate and said sheet.

45 4. A plate metal door for a railway car having an embossed panel pressed from the plane of the plate with flat margins surrounding said panel, an embossed panel pressed from the first mentioned panel with flat margins surrounding the last mentioned panel, said embossed panels conforming substantially to the shape of the door, a similarly embossed metallic sheet secured to said plate with the embossments projecting in the opposite direction to those of the plate, and a strut between said plate and said sheet.

50 5. A plate metal door for a railway car having an embossed panel pressed from the

plane of the plate with flat margins surrounding said panel, an embossed panel pressed from the first mentioned panel with flat margins surrounding the last mentioned panel, said embossed panel projecting in the same direction and conforming substantially to the shape of the door, a similarly embossed metallic sheet secured to said plate with the embossments projecting in the opposite direction to those of the plate, and a strut between said plate and said sheet.

6. A plate metal door for a railway car having an embossed panel pressed from the plane of the plate with flat margins surrounding said panel, an embossed panel pressed from the first mentioned panel with flat margins surrounding the last mentioned panel, said embossed panels projecting in the same direction and varying in depth and conforming substantially to the shape of the door, a similarly embossed metallic sheet secured to said plate with the embossments projecting in the opposite direction to those of the plate, and a strut between said plate and said sheet.

7. A plate metal door for a railway car having an embossed panel pressed from the plane of the plate with flat margins surrounding said panel, an embossed panel pressed from the first mentioned panel with flat margins surrounding the last mentioned panel, a metallic sheet secured to said plate, and a strut between said plate and said sheet.

8. A plate metal door for a railway car having an embossed panel pressed from the plane of the plate with flat margins surrounding said panel, an embossed panel pressed from the first mentioned panel with flat margins surrounding the last mentioned panel, said embossed panels projecting in the same direction and conforming substantially to the shape of the door, a metallic sheet secured to said plate, and a strut between said plate and said sheet.

9. In combination with the other elements of a railway dump car, a plate metal door having an embossed panel pressed from the plane of the plate with flat margins surrounding said panel, an embossed panel pressed from the first mentioned panel with flat margins surrounding the last mentioned panel, and a similarly embossed metallic sheet secured to said plate with the embossments projecting in the opposite direction to those of the plate.

10. In combination with the other elements of a railway dump car, a plate metal door having an embossed panel pressed from the plane of the plate with flat margins surrounding said panel, an embossed panel pressed from the first mentioned panel with flat margins surrounding the last mentioned panel, and a metallic sheet secured to said plate.

11. A plate metal door for a railway car having an embossed panel pressed from the plane of the plate with flat margins surrounding said panel, an embossed panel 5 pressed from the first mentioned panel with flat margins surrounding the last mentioned panel, and a metallic sheet secured to said plate adjacent its edges and at its center.

12. In combination with the other elements of a railway dump car, a plate metal door having an embossed panel pressed from the plane of the plate with flat margins surrounding said panel, and a metallic sheet secured to said plate.

13. A plate metal door for a railway car having an embossed panel pressed from the plane of the plate with flat margins sur-

rounding said panel, a metallic sheet secured to said plate, and a strut between said plate and said sheet.

20

14. In combination with the other elements of a railway dump car, a plate metal door having an embossed panel pressed from the plane of the plate with flat margins surrounding said panel, and a similarly embossed metallic sheet secured to said plate.

25

15. A plate metal door for a railway car having an embossed panel pressed from the plane of the plate with flat margins surrounding said panel, a similarly embossed metallic sheet secured to said plate, and a strut between said plate and said sheet.

30

CHARLES DAVID BONSALL.

DISCLAIMER

1,638,143.—*Charles David Bonsall*, Chicago, Ill. PANEL BRACING IN HOPPER DOORS FOR RAILWAY CARS. Patent dated August 9, 1927. Disclaimer filed April 6, 1931, by the assignee, *Union Metal Products Company*.

Hereby enters this disclaimer to that part of the claim in said specification which is in the following words, to wit:

“In combination with the other elements of a railway dump car, a plate metal door having an embossed panel pressed from the plane of the plate with flat margins surrounding said panel, and a metallic sheet secured to said plate.”

[*Official Gazette April 21, 1931.*]
